UNITED STATES PATENT OFFICE.

CHARLES YEOMANS HOPKINS, OF BORDESLEY GREEN, BIRMINGHAM, ENGLAND.

EMERGENCY-BOLT-OPERATING MEANS.

Application filed May 5, 1927, Serial No. 189,080, and in Great Britain May 31, 1926.

This invention relates to bolts, commonly known as panic bolts, as employed for emergency exit doors and for similar purposes, and of the type in which the release of the bolts is automatically effected by the pressure of a crowd towards the door which ordinarily bars its passage. The object of the invention is to facilitate the production of the said bolts whilst ensuring the efficacy of the 10 same.

The invention comprises the employment in combination with a pair of bolts or sliding bars adapted to be moved in opposite directions, of an actuating member which operates 15 with a sliding movement and engages the said bolts or bars through the medium of projections and inclined slots. Also the invention comprises the construction of the parts so that the said bolts or the engaging ends of the 20 same are not right and left handed, but the same bolt or the same form of bolt can be used on either side of the one actuating member.

In the accompanying sheet of explanatory drawings:—

25 Figure 1 is a sectional side elevation, and Figure 2 a plan of an emergency door bolt constructed in accordance with this invention, the bolts being shown in the withdrawn position.

30 Figures 3, 4 and 5 are perspective views illustrating the interengaging portions of the two bolts and the actuating member.

In the construction of a panic bolt as shown for use with an emergency exit door, the device comprises as is usual a pair of sliding bars, bolts or shoots *a*, of which one secures the upper and the other the lower end of the door. The adjacent ends of the said bolts are preferably cranked or cut away for the 35 admission between them of the inner end of the push piece or bolt actuating member *b*, the outer end of which is connected in any ordinary manner with the usual bar or rail *c* extending across the inner side of the door 40 to receive the pressure resulting in the release of the bolt for the use of the emergency or panic exit.

On the inner face of each of the said cranked portions of the bolts there is provided 45 an oblique projection *d* extending in an inclined direction across the bolt. The cranked ends of both bolts are precisely similar, there being no right and left handed dispositions of the projections *d*. When a pair

of the bolts are placed in position on opposite sides of the actuating member *b* they engage oppositely inclined slots *e* on such member, so that a sliding movement of the actuating member in a direction at right angles to the plane of the door produces opposite 55 longitudinal movements of the bolts.

The adjacent ends of the bolts and actuating member are carried by a suitably shaped and closely fitting body part *f* adapted to be secured to the inside face of the door. 60

To enable the actuating members to be operated by a watchman or other authorized person from the outside of the door, the end of the actuating member *b* opposite the bar *c* may be adapted in any convenient manner for 65 operation by a suitable key or like appliance inserted through an aperture in the front of the door. Obviously the mode of engaging the key and actuating members may be effected in a variety of ways. For example, a screw thread connection, or a bayonet joint connection may be used. In the construction shown the forward end *g* of the part *b* is screw-threaded. To this end can be detachably connected an internally screw-threaded 70 tool *h* (Figure 5) by which a pull or push can be imparted to *b* from the outer side of the door.

Having thus described my invention what I claim as new and desire to secure by Letters 75 Patent is:—

1. In emergency door bolts, the combination comprising a slidable actuating member formed on a pair of opposite sides with oppositely inclined slots, a pair of similarly 80 formed slidable bolt members movable in opposite directions at right angles to the actuating member, an oblique integral projection on each bolt member adapted to engage 85 one of the inclined slots of the actuating member, and a closely fitting body part adapted to enclose and support the adjacent portions of the bolt and actuating members, substantially as described.

2. In emergency door bolts as claimed 90 in claim 1, the combination with the actuating member of means whereby the said member may also be actuated by detachable means from the outside of the door, substantially as described.

In testimony whereof I have signed my name to this specification.

CHARLES YEOMANS HOPKINS.
